UNITED STATES PATENT OFFICE.

EDWARD J. ASCHINGER, OF OSHKOSH, WISCONSIN.

BENCH-CLAMP AND PLANING-VISE.

1,152,365.

Specification of Letters Patent. Patented Aug. 31, 1915.

Application filed October 3, 1914. Serial No. 864,849.

To all whom it may concern:

Be it known that I, EDWARD J. ASCHINGER, a citizen of the United States, residing at Oshkosh, in the county of Winnebago and State of Wisconsin, have invented new and useful Improvements in Bench-Clamps and Planing-Vises, of which the following is a specification.

This invention relates to a bench clamp 10 and planing vise, the primary object being to provide a single device which may be mounted upon a carpenter's bench or upon a heavy plank to serve as means for clamping a number of boards or other articles 15 together, or to serve as effective means for holding a board in position while it is being planed.

A further object of the invention is to provide a device of this character which is 20 adapted to hold a board being planed in a secure manner and yet without affording an obstruction which would prevent the plane from being operated throughout the length of the board, when planing either a 25 narrow edge or a broad side of the board.

The invention consists in the features of construction, combination and arrangement of parts, hereinafter fully described and claimed, reference being had to the accompanying drawing, in which:

Figure 1 is a side elevation of the device mounted upon a bench for use in holding a board to permit of planing one of its edges; Fig. 2 is a top plan view of the same; Fig. 3 is a side elevation of the device in use for holding a board when planing one of its broad faces; Fig. 4 is a top plan view of the same; and, Fig. 5 is a vertical sectional view on line 5—5 of Fig. 4.

In the drawing, the numeral 1 designates a work bench upon which the base 2 of my improved clamp device is mounted, though it is to be understood that the said base may be mounted upon a heavy board or plank, which might prove more convenient for outdoor work or the like. The base 2 is secured to the bench chiefly by means of a clamping bolt member 3 which has the squared portion 4 of its head engaged within the correspondingly shaped opening 5 in the base and projects downwardly therefrom through the vertical bench opening 6. An adjustable hand wheel 7 is mounted upon the protruding end of the bolt member 3 beneath a washer 8 which the said wheel is adapted to force against the under face of the bench.

in securing the base 2 to the upper face of the same. A plurality of wood screws 9 are also mounted within openings 10 provided in the base for engagement within the bench 60 to prevent rotation of the base upon the clamping bolt member.

The base 2 is adapted to be mounted at one end of the bench equidistant from its longitudinal side edges and it has a pair 65 of laterally spaced hinge lugs 11 and 12 formed upon its inner edge. The transversely extending body portion 13 of the movable member 14 of the device is provided medially with a hinge lug 15 which 70 is adapted to be pivotally mounted between the lugs 11 and 12 of the base upon the transverse pivot pin 16, which latter extends horizontally through the hinge lugs of the base and movable member and is detachably 75 mounted therein. Parallel arms 17 and 18 project outwardly from the ends of the body portion 13 of the movable member. The ends of the arms 17 and 18 are provided terminally with inwardly projecting, 80 alining extensions 19 and 20, the former being provided with an enlargement 21 forming a fixed clamp jaw, whereas the latter has a clamping screw 22 adjustably mounted therein. This screw is provided 85 upon its outer end with a handle 23 by which it may be operated, and has a movable jaw 24 swiveled upon its inner end for coöperation with the fixed jaw 21 in binding 90 boards or other articles therebetween. 95

The movable member or clamp, just described, is adapted particularly for use as a planing vise for use in holding a board in an upright position with the narrow edge to be planed disposed uppermost, as shown 100 particularly in Figs. 1 and 2 of the drawing. In this position the board is adapted to have its broad side faces engaged by the fixed and movable jaws of the clamp, and it should be apparent to those skilled in the art to which this invention appertains, that the clamp or movable member may be arranged at a slight angle to the horizontal so that the jaws of the same may engage the board mounted therebetween at such a 105 height above the bench that it will be secured most rigid, whereby lateral movement of the board will be prevented without permitting the jaws of the clamp to prove obstructions to the movement of the plane (not 110 shown).

The hinge lugs 11 and 12 of the base 2 are

provided upon their outer longitudinal faces with sharpened ribs 25 and 26 respectively whose active edges are adapted to be engaged with the end of a board, which may be placed flat upon the bench for the purpose of planing either of its broad faces, as shown particularly in Figs. 3 to 5 inclusive, it being understood that the movable member 14 must be thrown back into its inoperative position overlying the base before the board can be engaged in this manner with the ribs 25 and 26. The hinge lugs 11 and 12 thus present limiting shoulders for preventing horizontal movement of the board being planed and the ribs 25 and 26 constitute securing teeth for preventing vertical movement of the board, these teeth being disposed at only a slight distance above the upper face of the bench so that they may be engaged with a comparatively thin board without presenting obstructions. By the use of the clamp member 14 and the securing teeth 25 and 26 in the different operations of planing a board, the plane may be operated freely throughout the entire length of the board, in either case, without danger of being obstructed or dulled by engagement with the securing means. It should be apparent that the clamping member 14 is constructed with reference to the hinge lugs 11 and 12 of the base and their securing teeth in such a manner that the latter will not interfere with its movement into either its operative or inoperative position.

When the clamp member 14 is in its inoperative position, its jaws will project outwardly from the adjacent end of the bench, whereby the arms 18 may lie flat upon the base 2. The jaws thus will not be disposed in the path of movement of the plane and may also serve as a vise for securing a vertically disposed board, or the like, while it is being split longitudinally by the use of a rip-saw, or its upper end is being planed. It should also be apparent

that the clamp member may be removed for use in other capacities by withdrawing the securing pin 16, should this prove desirable in practice.

What is claimed is:

1. A device of the class described comprising a base, spaced lugs on the inner edge thereof and having teeth projecting forwardly therefrom, a clamping member pivotally connected with said lugs and adapted to be swung forwardly in alinement with said base and rearwardly in superimposed relation thereto, said clamp including spaced parallel arms, one of said arms being extended inwardly and terminating to provide a fixed jaw, a movable jaw carried by the other of said arms, and means for adjusting said jaw with respect to the fixed jaw. 50

2. A device of the class described comprising a base, a pair of relatively spaced hinge lugs formed upon one edge of the base, sharpened securing teeth formed upon said lugs to project outwardly therefrom, a movable clamp member including a transversely extending body portion arranged in parallel relation to the said edge of the base bearing the lugs, a hinge lug formed medially upon the said body portion and being rotatably mounted between the base lugs, a pair of parallel arms projecting outwardly from the opposite ends of the body portion of the clamp and being disposed outward with respect to the base lugs, a fixed jaw provided upon one of the said arms inwardly thereof, a movable jaw provided upon the other arm adjacent to the fixed jaw, and means by which the movable jaw may be adjusted with relation to the fixed jaw. 65

In testimony whereof I affix my signature in presence of two witnesses.

EDWARD J. ASCHINGER.

Witnesses:

GEO. HENKEL,
H. A. HENKEL.
